[57] CLAIM

The ornamental design for cap for sealing off an open end of a cartridge, as shown and described.

DESCRIPTION

FIG. 1 is a perspective view from one side and above of a first embodiment of a cap showing my new design; FIG. 2 is a perspective view from one side and above of a second embodiment of a cap showing my new design; FIG. 3 is a perspective view from one side and above of a third embodiment of a cap showing my new design; FIG. 4 is a perspective view from one side and above of a fourth embodiment of a cap showing my new design;

FIG. 5 is a perspective view from one side and above of a fifth embodiment of a cap showing my new design; FIG. 6 is a perspective view from one side and above of a sixth embodiment of a cap showing my new design; FIG. 7 is a perspective view from one side and above of a seventh embodiment of a cap showing my new design; FIG. 8 is a perspective view from one side and above of an eighth embodiment of a cap showing my new design; FIG. 9 is a top plan view of the cap shown in FIG. 3; FIG. 10 is a top plan view of the cap shown in FIG. 4; FIG. 11 is a top plan view of the cap shown in FIG. 5; FIG. 12 is a top plan view of the cap shown in FIG. 6; FIG. 13 is a top plan view of the cap shown in FIG. 7; FIG. 14 is a top plan view of the cap shown in FIG. 8; FIG. 15 is a top plan view of the cap shown in FIG. 2; FIG. 16 is a top plan view of the cap shown in FIG. 1; FIG. 17 is a side elevational view from below in FIGS. 10 and 14;

FIG. 18 is a side elevational view from below in FIGS. 9 and 13;

FIG. 19 is a side elevational view from below in FIGS. 12 and 15;

FIG. 20 is a side elevational view from below in FIGS. 11 and 16;

FIG. 21 is a side elevational view from above or right or left in FIGS. 9, 10, 13 and 14 or, from above in FIGS. 11, 12, 15 and 16;

FIG. 22 is a left side elevational view of FIGS. 11, 12, 15 and 16, the right side elevational view being a mirror image thereof;

FIG. 23 is a magnified diametrical cross-sectional view of the embodiments shown in FIGS. 1-4, for example taken on the lines 23—23 in FIG. 16;

FIG. 24 is a magnified diametrical cross-sectional view of the embodiments shown in FIGS. 5-8, for example taken on the line 24—24 in FIG. 14;

FIG. 25 is an underneath plan view of the embodiments shown in FIGS. 1 and 5;

FIG. 26 is an underneath plan view of the embodiments shown in FIGS. 2 and 6;

FIG. 27 is an underneath plan view of the embodiments shown in FIGS. 3 and 7;

FIG. 28 is an underneath plan view of the embodiments shown in FIGS. 4 and 8.
